ICE PICK

Application filed August 19, 1929. Serial No. 386,995.

This invention relates to certain new and useful improvements in ice picks, and has particular reference to that type of pick wherein the point is resiliently retained within the handle.

It is an object of this invention to provide an ice pick wherein the parts are positively held together, and whereby such parts may be assembled at a minimum cost.

It is a further object of this invention to provide a means for preventing the handle from splitting under the repeated shocks caused by the use of the ice pick thereby providing great durability of the completed article.

In the drawing forming part of this specification wherein corresponding parts are designated by similar reference characters throughout the several views;

Fig. 1 shows a sectional view of an embodiment of the invention in completed form.

Fig. 2 shows a fragmentary sectional view with the parts in position ready to have the sleeve forcibly expanded about the cup.

Fig. 3 shows a fragmentary section of the completed device, showing how the interior movement of the rod is limited by the shock diffusing stop.

The ice pick comprising this invention includes a handle 10 of wood or other suitable material provided with a longitudinal passage having an interior portion 11 of smaller diameter and an exterior portion 12 of larger diameter with a shoulder 13 formed therebetween.

A pointed rod 14 is yieldably retained in this passage and is adapted for longitudinal movement therein, its movement into the passage being limited by a ball 15 placed at the interior end of passage 11, so that in use the ball receives the shocks from the rod and diffuses such shocks throughout the handle eliminating the tendency of the handle to split.

The means for yieldably retaining rod 14 in handle 10 comprises a cup 16 snugly fitted in passage 12 against the shoulder 13 as shown in Fig. 2. A tubular metallic sleeve 17 of thinner or weaker material than the cup 16 is snugly fitted into the passage 12 as shown in Fig. 2, having an open end 15 of

lesser interior diameter than the exterior diameter of cup 16. Sleeve 17 is then forcibly pressed against cup 16, whereupon end 18 will be expanded about cup 17 into the handle forming an anchor 19 positively retaining the sleeve within the handle as shown in Figs. 1 and 3.

The sleeve 17 has a closed end 20 having an opening 21, and a corresponding opening 22 is formed in cup 16, these openings 21 and 22 forming a means for slidably guiding the rod 14. Ears 23 pinched into rod 14 prevent said rod from passing through opening 21, and a washer 24 is placed on the outer side of ears 23 to assist in such retention. Another washer 25 is placed on the inner side of ears 23 and serves as a base for one end of a compression spring 26 placed within the sleeve 17 about the rod 14, the other end bearing against cup 16.

To add weight to the handle a heavy cap 27 may be attached to the end of handle 10 by a screw 28 and may be hexagonal in shape to prevent the device from rolling when placed on a table or other surface. Lugs 29 on the inside of cap 27 are pressed into the end of the handle when the cap is affixed thereto, and serves to prevent the turning or slipping of the cap on the handle.

To operate the device, the point of rod 14 is placed on the ice where it is desired to split it, and the handle is repeatedly pressed forcibly down against the rod, whereby to drive the point into the ice to split it.

It will be noted that this invention provides an efficient type of ice pick that may be manufactured and assembled at a minimum expense, wherein the parts are positively held together and wherein the device will be of great durability due to the elimination of the tendency of the handle to split while in use, but it will be understood that the invention is not limited to the details as illustrated above, but that modifications may be made within the limits of what is claimed.

Having thus set forth the nature of the invention, what is claimed is:

1. An ice pick of the type described comprising a handle, a tubular opening in said handle, said opening being of a greater di-

ameter at its exterior end and of lesser diameter at its interior end, a shoulder formed in said handle between the small and large portions of said opening, a stop at the interior 5 end of the small portion of said opening, a cup fitted in said large opening against said shoulder, said cup having an opening therethrough, an open ended capped tubular member having its interior diameter of lesser diameter than the exterior diameter of said cup, the open end of said tubular member being 10 expanded about said cup to form an anchor locking said tubular member in said handle, said tubular member having an opening 15 through its capped end, a pointed rod slidably passing through said openings in said cup and tubular member in position to have its inner movement limited against said stop, a compression spring in said tubular member, one end of said spring bearing against 20 said cup, ears on said rod for retaining a washer on each side of said ears, the other end of said spring bearing against one of said washers and tending to urge said rod 25 away from said stop.

2. An ice pick comprising a pointed rod, an ear on said rod, a handle having a passage for slidably receiving said rod, said passage having an enlarged portion, a shoulder 30 formed at the inner end of said enlarged portion, a cup inserted in said enlarged portion against said shoulder, said cup having an opening permitting sliding movement of said rod therethrough, a sleeve in said enlarged portion, the inner end of said sleeve 35 being expanded about said cup to anchor said sleeve in said handle passage, a compression spring in said sleeve between said cup and said ear, said sleeve having a capped end with an opening slidably guiding said rod therethrough, said ear limiting the exit movement of said rod.

3. An ice pick comprising a handle having a passage therein, a shoulder in said passage, 45 a cup bearing against said shoulder, a capped metallic sleeve expanded about said cup to form an anchor therefor in said handle, said cup and the capped end of said sleeve being provided with openings, a pointed rod 50 passing through said openings, means on said rod for retaining said rod within said sleeve, and a compression spring about said rod within said sleeve tending to urge the rod out of said handle.

4. An ice pick comprising a handle having a passage therein, a shoulder in said passage, a cup bearing against said shoulder, a capped metallic sleeve expanded about said cup to form an anchor therefor in said handle, 60 said cup and the capped end of said sleeve being provided with openings, a pointed rod passing through said openings, an ear on said rod for limiting the exit movement of said rod within said sleeve, and a compression 65 spring about said rod within said sleeve bear-

ing against said ear for urging the rod out of said handle, and a stop at the inner end of said passage for absorbing and diffusing the shocks from said rod throughout said handle.

5. An ice pick comprising a rod, a handle of compressible material having a passage therein, means for yieldably retaining said rod for movement within said passage, and a shock diffusing stop limiting the movement of said rod into said handle, said stop comprising a ball placed at the interior end of said passage and preventing said handle from splitting.

6. An ice pick comprising a handle of compressible material having a longitudinal passage therein, the exterior portion of said passage being of greater diameter than the interior portion and forming a shoulder between said portions, a ball at the interior 80 end of said interior portion forming a shock diffusing stop, a cup having an opening therethrough fitted in said exterior portion against said shoulder, a capped sleeve fitted in said exterior portion and having an open 85 end, said open end being expanded about said cup into said handle and forming an anchor for said sleeve, the capped end of said sleeve likewise having an opening therethrough, a pointed rod slidably passing 90 through said openings against said stop, an ear on said rod for retaining said rod within said openings, and a compression spring about said rod within said sleeve for urging 95 said rod away from said stop.

7. An ice pick comprising a handle of compressible material having a longitudinal passage therein, the exterior portion of said passage being of greater diameter than the interior portion and forming a shoulder between said portions, a guide member having an opening therethrough seated against said shoulder, a metal sleeve in said exterior portion and having an open end expanded about said guide member to provide an enlarged end forming an anchor for the sleeve in the handle, a pointed rod guided for sliding movements in the sleeve and said guide member, a spring tending to move the rod outwardly, and means for limiting the outward movements of the rod.

8. An ice pick comprising a handle having a passage therein, a guide member mounted in said passage, a metallic sleeve expanded about said member to form an enlarged end providing an anchor for the sleeve in the handle, a pointed rod guided for longitudinal sliding movements in the guide member and sleeve, a spring tending to force the rod outwardly, and means for limiting said outward movement.

In testimony whereof I affix my signature.

BESSIE R. PLATT,
